UNITED STATES PATENT OFFICE.

BENJAMIN F. FITCH, OF EVANSTON, ILLINOIS.

VEHICLE BODY LIFTER.

Original application filed March 22, 1922, Serial No. 545,668. Divided and this application filed April 16, 1923, Serial No. 632,239.

To all whom it may concern:

Be it known that I, BENJAMIN F. FITCH, a citizen of the United States, residing at Evanston, in the county of Cook and State 5 of Illinois, have invented a certain new and useful Improvement in a Vehicle Body Lifter, of which the following is a full, clear, and exact description, reference being had to the accompanying drawings.

10 This application is a division of my co-pending application, Serial No. 545,668, filed March 22, 1922. The present invention relates to vehicle body lifters such as are adapted for engaging a load which is arranged to be suspended at four points from an overhead hoisting mechanism.

One of the objects of my invention is the provision of mechanism for permitting load engaging elements, particularly where a 20 cradle is employed, to be directly connected with a load. The arrangement of beams forming the cradle is such as to prevent the use thereof for transmitting load stresses between the load and lifting cables.

25 The means for carrying out my invention will be hereinafter described in connection with the accompanying drawings and the essential features will be summarized in the claims.

30 In the drawings, Fig. 1 is a side elevation of a container showing a hoisting element embodying my invention above the container; Fig. 2 is an end view of the hoisting element and container shown in Fig. 1; Fig. 35 is a fragmentary view on an enlarged scale showing the preferred means for connecting the cradle to the load supporting hooks; Fig. 4 is a detail on an enlarged scale of the hinge connection for the trans- 40 verse beams; Fig. 5 is a section taken on the lines 5—5 in Fig. 4; Fig. 6 is a horizontal section on the line 6—6 in Fig. 3.

One of the uses of my invention is illustrated in Fig. 1 wherein 10 indicates a container in the form of a removable body having provision adjacent the upper corners thereof for receiving load supporting elements which are adapted to be engaged by hoisting mechanism for raising and trans- 50 porting the container. In handling freight by the use of such containers, the usual practice is to engage the container at the top. Accordingly, to transmit lifting stresses to the floor of the container, I have shown a 55 plate 11 which the hoisting mechanism is

adapted to engage as being connected to the base of the container by vertical strips 12 and diagonal strips 13. These plates are attached to the container and in the form illustrated are provided with a recess or 60 pocket across which I have shown a member 14 which is adapted to be engaged by the hoisting elements.

To effect a simultaneous engagement of the four load engaging members 18, I have 65 illustrated a cradle comprising longitudinal beams 25 which are connected at the ends thereof by hinged transverse beams 26, and 27 respectively. The longitudinally extending beams project beyond the ends of the 70 load, while the transverse beams are hinged at the mid-portion of the cradle, as at 28, so that when the cradle is not supporting a load, as illustrated in Fig. 1, and by the full lines in Fig. 2, the members 25, 26 and 27 75 lie approximately in the same plane. In this position, the load engaging members or hooks 18 clear the sides of the container so that the cradle may be dropped over a load by lowering the load supporting 80 cables 30.

To hold the transverse beams in extended position, that is, to maintain the transverse beams in the same plane as the longitudinal beams, I have shown a yoke 31 which supports a hinge pin 28 and which is provided with feet 32 that are adapted to engage the beams 26 and 27 for limiting the downward motion. Suitable cables 33 are connected to the yoke members for controlling the opening and closing of the cradle. Thus, when movement of the hoisting cables is suspended, and the cables 33 are slackened, then the weight of the end members causes the cradle to open until the position shown in full lines 95 in Fig. 2 is attained.

To attach the load engaging members or hooks 18 to the longitudinal beams, I may employ a U-bolt 35 the intermediate portion of which extends around the shank of the hook and the ends of which project through openings in the beam 25. The U-bolt may then be locked to the beam by nuts 37. By attaching the load engaging elements to the ends of the supporting cables and by positioning such elements on the beams 25 so as automatically to register with the pockets in the plates 11, it is obvious that all load stresses are transmitted directly through the elements or hooks and the hoisting cables. 105 110

Accordingly, the cradle beams may be of light construction sufficient only to hold the hooks in proper position for registration with the pockets in the load.

8. To engage a load with a hoisting device embodying my invention, the cradle while in open or extended position is lowered until the hooks 18 are beneath the pockets in the load. Then the cables 30 may be 10 raised whereupon the load is elevated and the hinge members 26 and 27 are automatically held in the position indicated by the broken lines in Fig. 2.

From the foregoing description, it will 15 be seen that my invention provides a mechanism for simultaneously bringing a plurality of load engaging members on a hoisting cradle in registration with cooperating members on the load, thus enabling the 20 load to be engaged and raised by one man and obviating the necessity for individual attention to each load engaging member. Moreover, the cradle construction illustrated, permits the load to be suspended without any of the load stresses being transmitted through the cradle beams.

I claim:—

1. In combination, a cradle having side beams and hinged end beams, load engaging members mounted on the side beams, and hoisting cables attached directly to said members, whereby the side frames are relieved of lifting stresses.

2. In combination, a cradle having longitudinal beams, hinged beams connecting the ends thereof, load engaging members carried by the longitudinal beams and projecting above and below said beams, and cables connected directly with the members above 40 the beams, whereby the longitudinal means are relieved of lifting stresses.

3. A cradle having in combination longitudinal beams and hinged end beams, load engaging hooks carried by the longitudinal beams adjacent the ends thereof, the hooks being turned inwardly to engage a load when the cradle is buckled, and means for attaching hoisting cables to said hooks whereby the load stresses are carried only 50 by the hooks and cables.

4. The combination with four elevating cables, of four load engaging members attached directly to said cables respectively, a pair of members each connecting two of 55 the load engaging members, and means for laterally moving said pair of members, whereby said pair of members are relieved from lifting stresses.

5. The combination with four elevating cables, of four load engaging members attached to said cables respectively, a pair of side bars each connecting two of the load 60 engaging members, and hinged cross-bars

connected to the side bars for laterally moving them, the lifting stresses being carried independently of the side bars. 65

6. In a device for lifting loads, the combination with four load engaging members adapted to engage the load and having elevating devices attached directly to them, a 70 pair of side bars each connected to two of said load engaging members to position them, but independent of the lifting stresses, and means for spreading the side bars.

7. In a device for lifting loads, the combination with four load engaging members adapted to engage the load, elevating devices attached directly to said members, a 75 pair of side bars each connected to two of said load engaging members and two sets 80 of hinged transverse bars for spreading the side bars.

8. In combination, a cradle having side beams and hinged end beams, load engaging members carried by the side beams, load 85 supporting cables attached to said members whereby lifting stresses are transmitted from the load directly to the lifting cables, the hinged connection for said end beams comprising a member having lateral extensions adapted to engage said members for 90 limiting relative movement thereof to hold the cradle in open position, and buckling cables attached to said connections.

9. In combination, a cradle having side 95 beams and hinged end beams, hooks carried by said beams and adapted to engage a load, cables attached to the upper end of said hooks wherefore load stresses are transmitted from the load directly to said cables, U-bolt members around the shank of each hook for connecting it to the side beams, cables attached to the hinged connections for the end beams for buckling the load, and means associated with said extension 100 105 for engaging the end beams and limiting the relative movement thereof, said means being arranged to hold the cradle normally in open position.

10. In combination, a cradle having side 110 beams, hooks carried by said beams and adapted to engage a load, cables attached to the upper end of said hooks wherefore load 115 stresses are transmitted from the load directly to said cables, and U-bolt members around the shank of each hook for connecting it to the side beams.

11. A lifting device having a positioning beam, a hook carried by said beam and adapted to engage a load, a cable attached to the upper end of said hook, and a U-bolt 120 around the shank of the hook for connecting it to the positioning beam.

In testimony whereof, I hereunto affix my signature.

BENJAMIN F. FITCH.
